UNITED STATES PATENT OFFICE.

ANTHONY EDWARD LANG, OF BUFFALO, NEW YORK.

SHOWER-BATH CURTAIN.

1,159,507.

Specification of Letters Patent.

Patented Nov. 9, 1915.

Application filed June 10, 1915. Serial No. 33,285.

To all whom it may concern:

Be it known that I, ANTHONY E. LANG, a citizen of the United States, and resident of Buffalo, county of Erie, State of New York, have invented certain new and useful Improvements in Shower-Bath Curtains; and I do hereby declare the following to be a full, clear, and exact description of the invention, such as will enable others skilled 10 in the art to which it appertains to make and use the same.

The invention relates to curtain attachments for bath tubs and the like, and has for its object to provide a simple, cheap and efficient device of the character described, adapted to be supported on the rim of a bath tub or other receptacle capable of use in connection with a shower, needle, spray, or other similar character of bathing apparatus, said curtain serving to prevent the water being splashed or diverted outside of the confines of the tub. To this end, the invention comprises a series of upright standards, provided with means for slidably supporting the same on the rim of the tub or other receptacle, said means preferably taking the form of spring clips which hold the standards in upright position, and a curtain provided with means, preferably in the form 20 of exterior pockets, in which the standards engage to suspend the curtain about the tub, so that its lower edge lies within the walls of the tub, the standards and the curtain adapted to be disposed in circumferential 25 relation about the tub, when in use, and to be slid along the edge of the tub and assembled along the rear wall or other out of the way portion of the tub when not in use.

The invention is illustrated in the accompanying drawings, in which,

Figure 1 is a perspective view of a bath tub having the curtain applied thereto in position for use, a section of the curtain being broken away to show certain interior arrangements. Fig. 2 is a vertical transverse section through the tub and curtain.

Referring to the drawings, 1 indicates a bath tub of standard type, which is provided with the usual rim about its upper edge. 50 Slidably supported on the rim of the tub is a series of vertical standards 2, each of which is preferably formed of a metal strip or rod extending for a considerable height above the rim and also for a relatively short 55 distance below the rim and provided at its lower end with a bend or fold parallel with

the body portion and terminating in a spring clip 3, which hugs the rim of the tub and rests against the outside wall of the tub. The spring clip 3 associated with the lower 60 end of the body portion of the standard 2, therefore, serves to hold the standard in vertical position on the tub rim and admits of the several staves being slidably adjusted about the rim in spaced relation, or to be 65 moved along said rim to some desired location where the standards will be collected and retained without interfering with the normal use of the tub.

Removably supported by the standards 2 70 is a curtain 4, which is adapted to be extended about the rim of the tub, in the manner illustrated in Fig. 1, with its lower edge lying within and against the inner walls of the tub so as to prevent any water splashing 75 from the tub or from the space defined by the curtain and the tub. A convenient means for supporting the curtain on the standards 2 comprises pockets 5, formed by stitching strips of fabric on the exterior of the curtain, each of said pockets 5 having a length substantially equal to the portion of the standard 2 which projects above the tub rim. The curtain is formed of a length of fabric having a substantial hem at its top edge and 80 the pockets formed as described at intervals about its exterior surface, one vertical edge of the curtain having a pocket formed therein and the other vertical edge having a pocket formed a short distance to one side 85 of the edge to permit the vertical edges of the curtain to overlap, when the curtain is drawn around the tub, as shown in Fig. 1. The overlapping edges may be secured temporarily together by any appropriate means 90 so that the opening between said edges is effectively closed when the curtain is in use.

In order to adapt the curtain for use with a tub having accessories attached thereto, such as a seat for the bather, and a soap or sponge receptacle, the lower edges of the curtain are slitted vertically to form flaps 7 which overlie the adjacent portions of the seat and the receptacle, as illustrated in Fig. 1, which nevertheless effectively prevent any 100 water splashing outside of the apparatus.

It will be apparent that the apparatus as described may be used with an overhead shower or spray, or with a spray device connected with the usual water supply faucet 110 by means of a flexible pipe, held by the bather, or by any of the ordinary types of

spray bath devices. When the curtain is to be used by a bather, it is drawn out about the rim of the tub, by sliding the standards 2 and the spring clips thereof about the rim, 5 until the vertical edges of the curtain approach each other. The bather then enters the tub and draws the said vertical edges into overlapping relation shown in Fig. 1 and secures the overlapping edges together 10 by a pin or other fastener, and the device is then in proper relation to permit the bather to employ any of the well known types of spraying devices, without danger of the water either from the spraying device or 15 from the tub splashing on the walls or floor of the apartment. When the bather desires to leave the tub, the overlapping vertical edges of the curtain are disconnected and separated and the curtain may be left in its 20 extended relation to dry. In order to permit the tub to be used for an ordinary bath, not involving the use of the spray and to dispose the curtain so that it will not interfere with the bather, the supporting standards and the curtain may be moved along the rim of the tub until the device is disposed in closely compacted relation at the rear side of the tub or at one end thereof. The sliding movement of the curtain and its 25 supporting standards, and the closing of the vertical edges or flaps of the curtain may be readily effected by means of straps or the like 8, which are attached to each of the vertical edges and permit the parts to be 30 drawn along the supporting tub rim in either direction, as will be apparent.

It will be noted that the curtain is loosely supported on the standards by the pockets 5 into which the standards fit, so that the curtain may be readily removed for washing or repair, by merely lifting the same off of the standards, and likewise the curtain may be as readily reapplied to the tub by engaging the pockets successively with the corresponding standards. Obviously, the curtain may be made of any desired height and of any appropriate material. The standards 40 also will be made of suitable material, capable of being formed with the rim-engag-

ing clips and will have a vertical height 50 sufficient to accommodate the predetermined height of the curtain.

What I claim is:—

1. A device of the character described, comprising a series of separate upright standards having spring clips adapted to slidably engage the rim of the tub, and a divided curtain provided with means for suspending it from said standards; whereby the curtain may be stretched about the tub 60 when the standards are slidably spaced apart, and collapsed when the standards are slidably assembled together on the rim.

2. A device of the character described, comprising a series of upright standards 65 having spring clips adapted to engage the rim of the tub, and a curtain provided with pockets to receive the standards and support the curtain so that its lower edge lies within the walls of the tub.

3. A device of the character described, comprising a series of separate upright standards, each provided at its lower end with means clamping it in sliding relation to the rim of the tub, and a curtain provided 75 with means engaging said separate standards to suspend the curtain in either extended or collapsible relation within the walls of the tub.

4. A device of the character described, 80 comprising a series of upright standards having spring clips adapted to engage the rim of the tub, and a curtain provided with exterior pockets to receive the standards and support the curtain so that its lower 85 edge lies within the walls of the tub.

5. A device of the character described, comprising a series of upright standards having spring clips adapted to engage the rim of the tub, and a curtain provided with 90 means engaging said standards to suspend the curtain so that its lower edge lies within the walls of the tub, said curtain having incisions normal to its edge to provide openings and flaps adjacent to accessories on the 95 tub walls.

In testimony whereof I affix my signature.
ANTHONY EDWARD LANG.
